UNITED STATES PATENT OFFICE.

HERBERT S. JANDUS, OF DETROIT, MICHIGAN, ASSIGNOR TO THE C. G. SPRING & BUMPER COMPANY, OF DETROIT, MICHIGAN, A CORPORATION OF DELAWARE.

DESIGN FOR A CLAMP PLATE.

Application filed May 3, 1928. Serial No. 26,553. Term of patent 14 years.

To all whom it may concern:

Be it known that I, HERBERT S. JANDUS, a citizen of the United States, residing at Detroit, in the county of Wayne, and State of Michigan, have invented a new, original, and ornamental Design for Clamp Plates, of which the following is a specification, reference being had to the accompanying drawing, forming part thereof, wherein—

Fig. 1 represents a side elevation and Fig.

2 represents a front elevation of a clamp plate exhibiting my new design. A bolt head for retaining the clamp plate is shown in dotted lines.

I claim:—

The ornamental design for a clamp plate, substantially as shown.

HERBERT S. JANDUS.
